UNITED STATES PATENT OFFICE.

JACOB C. HUNSINGER AND WILLIAM ENSMINGER, OF LAUREL, INDIANA,
ASSIGNORS OF ONE-THIRD TO FRANK H. BATT, OF SAME PLACE.

POULTRY-CRATE.

SPECIFICATION forming part of Letters Patent No. 536,954, dated April 2, 1895.

Application filed January 9, 1895. Serial No. 534,338. (No model.)

To all whom it may concern:

Be it known that we, JACOB C. HUNSINGER and WILLIAM ENSMINGER, citizens of the United States, residing at Laurel, in the county of Franklin and State of Indiana, have invented certain new and useful Improvements in Poultry-Crates; and we do hereby declare that the following is a full, clear, and exact description of the same, reference being had to the annexed drawings, making a part of this specification, and to the letters of reference marked thereon.

The present invention has relation to that class of shipping crates particularly designed for the transportation of poultry and in which the crate is composed of hinged sections adapted to fold down upon the base or floor of the crate when not in use for the purpose of economy in space in packing and transporting.

It is the purpose of the invention to so construct the several hinged sections of the crate that the smallest possible space may be occupied when folded together, and consists in a crate constructed substantially as shown in the drawings and hereinafter described and claimed.

Figure 1 of the drawings is a perspective view of a crate showing the hinged sections extended and in position to enable the crate to be used for containing and transporting poultry; Fig. 2, a similar view showing the hinged sections folded down upon each other; Fig. 3, a transverse section thereof taken on line xx of Fig. 2.

In the accompanying drawings A represents the base or floor of the crate having rigidly secured to its ends brackets B, which brackets have slots a terminating at their inner ends in depressions b .

To the brackets B are hinged end-sections C, which together with said brackets form the ends of the crate when in the position shown in Fig. 1 of the drawings.

The section D which forms the top of the crate has hinged to its under side the sections E F so that said sections will nicely fold against the under side of the top section, thereby materially economizing space when the crate is folded.

The ends of the sections E F have pins c

which project into the slots a , said pins serving the double function of guides for the hinged sections and also as means for locking them in a folded position when in engagement with the depressions b . These depressions also serve to bring the hinged sections E F down nearer to the base or floor A, when the pins are in engagement with the depressions, as shown in Fig. 2. The base or floor A is provided with stops d to limit the extent with which the sections E F may be pulled out and also serve as braces thereto when in an elevated position shown in Fig. 1.

The sections D E F may consist of suitable frames covered with wire gauze or may be constructed in any well known and preferred manner, and when the sections are folded together as shown in Fig. 2, they are secured against unfolding by the hinged sections C which are adapted to fold down upon the top section D and are fastened thereto by means of hinged bails G having eyes e which engage pins f upon the sections C, thus providing a very compact crate when folded and materially economizing in space. Such a crate is also simple in construction and may be manufactured at a greatly reduced cost and the sections may be quickly extended with little trouble for immediate use and may be as readily folded together for packing and transporting.

The end sections C are considered of importance, as they not only form the ends of the crate when extended, but are adapted to fold down upon the upper side of the section D to retain said section in position.

Having now fully described our invention, what we claim as new, and desire to secure by Letters Patent, is—

1. A folding poultry crate, consisting of a suitable base or floor, slotted brackets rigidly connected to the ends thereof, sections hinged to the brackets, a top-section and side-sections hinged thereto, said side-sections having guide-pins which engage with the slots in the brackets, substantially as and for the purpose set forth.

2. A folding crate, consisting of a suitable base or floor, slotted brackets connected to the ends thereof and having depressions at their inner extremities, and suitable hinged

- sections to form the top, sides and ends of the crate, said side-sections having pins to engage with the slots in the brackets and with the depressions thereof, substantially as and for the purpose described.
3. A folding crate, consisting of a base or floor, slotted brackets connected to the ends thereof, folding sections hinged to the brackets, a folding top having hinged sides with guide pins engaging the slots in the brackets, fastening devices for securing the hinged sections upon the brackets down upon the top

section, and stops upon the base or floor of the crate to hold the side sections in an upright position, substantially as and for the purpose 15 described.

In testimony that we claim the above we have hereunto subscribed our names in the presence of two witnesses.

JACOB C. HUNSINGER.
WM. ENSMINGER.
